UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed May 10, 1922. Serial No. 559,732.

To all whom it may concern:

Be it known that I, WILLIAM L. MCGRATH, a citizen of the United States, residing at Elmira, in the county of Chemung and State of New York, have invented certain new and useful Improvements in Engine Starters, of which the following is a specification.

My invention relates to engine starters and to that part thereof known as the drive or transmission, located between the prime mover such as an electric motor and a part of the engine to be started such as the fly-wheel thereof. The drive with which my invention is concerned is of that type exemplified by Bendix Patent No. 1,125,935 issued on January 26, 1915, characterized, among other features, by a coiled drive spring between the driving shaft and the driven shaft which latter is the screw shaft on which a pinion engaging the fly-wheel is mounted. The object of my invention is to provide means to support the first coil, preferably at each end, of the drive spring in such manner as to relieve the fastening means or anchoring screws or bolts from flexure or bending loads when the spring winds up in the starting operation, leaving as the only load to be taken by such screws a plain shear load which is easily resisted by such screws. Another resulting advantage is to prevent fatigue of the metal of the screws which is caused by flexure thereof, inasmuch as such flexure is overcome by the use of my invention.

Speaking in general terms, my invention, in its broader aspect, consists in providing means for supporting the first coils of the spring at a suitable point, such as 90° angularly displaced from the anchoring screws, whereby the torque through these coils of the spring will result in a load on the screws at right angles thereto, thereby preventing flexure of such screws. These supporting means may constitute an integral part of the driving and driven heads to which the ends of the drive spring are anchored but in practice and for convenience in manufacture, I prefer to provide such means as a separate part or member such as a clip, suitably secured to said heads.

In the drawings Fig. 1 is an elevation of a starter system illustrating a drive embodying my invention; Fig. 2 another ele-

vation showing the parts thereof in section; Fig. 3 is a sectional plane on the line 3-3 of Fig. 2; Figs. 4, 5 and 6 cross-sections on the corresponding section lines indicated on Fig. 1; Fig. 7 is an end elevation of the supporting clip, looking at one end thereof; Fig. 8 a similar view viewed from the other end; Fig. 9 a plan view thereof; Figs. 10 and 11 sections of the clip on the corresponding section lines indicated in Fig. 7; Fig. 12 a plan view of the clip in blank form partially completed and before being rolled up or formed as the final clip; Fig. 13 a sectional elevation of a modified form of construction; Fig. 14 a cross-section on the line 14-14 of Fig. 13; Fig. 15 a sectional elevation of another modified form of construction and Fig. 16 a cross-section on the line 16-16 of Fig. 15.

It will be understood that my invention, in its broader aspect may partake of different forms of embodiment but for the purpose of a clear and definite description I will first describe the construction illustrated in Figs. 1 to 12 as a simple, efficient and successful embodiment of the invention without intending to restrict myself thereto in so far as the broad claims are concerned. It will also be understood that the supporting means may be and by preference are provided at the end coils at both ends of the drive spring, but that a measure of my invention may be obtained by employing such supporting means at one end only thereof.

Referring to the embodiment of my invention illustrated in Figs. 1 to 12 and first briefly describing the engine starter structure, the same comprises an electric motor 1 having an extended armature shaft 2 on which is mounted a hollow screw shaft 3, a pinion 4 adapted to mesh with the fly-wheel 5, a driving head 6, and a drive spring 7 whose opposite ends are fastened or anchored to the driving head 6 and to the driven head 8 of the screw shaft by the screws or studs 9 and 10, respectively. The supporting means at the ends of the drive spring are similar in structure but reversed in position. Each clip comprises a strip of sheet metal 11 which originally has the form shown in Fig. 12. This strip is provided with a hole 12 through which the screw passes and is also provided with extensions 13 and 14 which are turned so

as to bear against the inner face of the head to which the clip is applied, thereby preventing displacement or rocking movement of the clip. The longer or extended 5 end of the strip is folded twice upon itself so as to form a projection 15 between the first coil and the side of the head to which the clip is attached, as clearly shown in Figs. 4, 5 and 6. In practice and by preference 10 the construction and arrangement are such that this projection is located as shown, that is at a point displaced approximately 90° angularly from the anchoring screw.

In applying the clip, this is done obviously 15 before the spring and screws are applied. The clips are placed upon the heads with the hole 12 in register with the screw holes in the heads which holes and screws properly locate the clips and also secure them in 20 place. The spring and screws are now applied and this particular assembly is then complete.

In the starting operation of this type of drive the spring winds up, which means that 25 the first coils, in particular, tend to wind down upon the heads. When my supporting means or clips are employed, the first coils are prevented from winding down close upon the heads, particularly at the point 30 where the projection 15 is located, with the result that the torque transmitted through the spring is at right angles to the longitudinal axis of the screws, that is, there is merely a shear strain or load which can 35 be easily resisted by the screws and that there is no flexure load applied to these screws. Heretofore in this type of drive the resulting load applied to the screws has been the component of a flexure load and a 40 shear load, which tended to bend or break the screws and also cause fatigue therein.

My invention in its broadest aspect may be embodied in quite different structures from that above described, such as are shown 45 in Figs. 13 to 16. As shown in Figs. 4, 5 and 6 the heads are of smaller diameter than the inside diameter of the first coils, but according to the modified forms of construction these heads are made of the same 50 diameter as the first coils of the spring and either the spring or the inner portions of the heads are made of special formation in order that the final result will be the supporting of the first coils in such manner 55 that the torque will result in a load on the anchoring means or screws at right angles thereto, thereby accomplishing the objects of the invention in its broadest aspect.

Referring to Fig. 13 the driving head 60 16 and the driven head 17 are made of the same diameter as the opening through the end coils of the spring. This spring 18 instead of being a cylindrical helix is wound to the form shown in Fig. 13, that is, conical 65 in longitudinal section. As a result the end

coil are properly supported by the heads themselves and the winding down of the spring in the starting operation is permitted by the special form of the body of the spring. 70

According to the modification of Fig. 15 the driving head 19 and the driven head 20 are also made of the same diameter as the opening through the end coils of the spring 21, but the inner adjacent ends of these 75 heads have reduced tapers 22 and 23, respectively, as shown in Fig. 15. The spring 21 when in normal condition is a helix but in operation the coils on winding down are permitted by such tapered ends of the heads 80 to wind inwardly towards or upon such tapers.

The drive spring is a helical spring and its coils have the cross section shown, that is with a greater height than width. Without the provision of my supporting means, there is considerable lever action of the spring upon the anchoring screws, with the result that the screws are flexed in the winding down of the spring in the cranking operation and are sometimes thereby broken. My supporting means avoids any possibility 90 of this flexure and breakage and the screws are thereby protected. 95

I claim:

1. In an engine starter drive, a helical drive spring whose coils have a greater height than width in cross section, an anchoring means for an end of such spring, in combination with means for supporting 100 the first coil at such end in such manner as to avoid lever action on such anchoring means and consequent flexure thereof.

2. In an engine starter drive, a helical drive spring whose coils have a greater height than width in cross section, and an anchoring screw engaged by an end of the spring, in combination with means for supporting the first coil at such end in such manner as to avoid lever action on such 105 screw and consequent flexure thereof.

3. In an engine starter drive including a driving shaft having a drive head, a driven shaft having a driven head, a driving member mounted on the driven shaft, a helical drive spring whose coils have a greater height than width in cross section, and screws for anchoring the ends of the springs to the heads in combination with means for supporting the end coils of such spring in 110 such manner as to avoid lever action on the screws and consequent flexure thereof.

4. In an engine starter drive including a driving shaft having a drive head, a driven shaft having a driven head, a driving member mounted on the driven shaft, a helical drive spring whose coils have a greater height than width in cross section, and screws for anchoring the ends of the springs to the heads in combination with a support 115 120 125

interposed between the end coils of such spring and the heads of points thereon approximately 90° removed from the connection between the screws and the spring.

5. In an engine starter drive including a driving shaft having a drive head, a driven shaft having a driven head, a driving member mounted on the driven shaft, a helical drive spring whose coils have a greater 10 height than width in cross section, and screws for anchoring the ends of the springs to the heads in combination with curved clips secured to said heads by said screws and having projections located adjacent the 15 inner surfaces of such end coils for supporting the end coils in such manner as to avoid lever action on the screws and consequent flexure thereof.

6. In an engine starter drive including a driving shaft having a drive head, a driven shaft having a driven head, a driving member mounted on the driven shaft, a coiled drive spring operatively connecting the two heads, and screws for anchoring the ends of the spring to the heads, in combination with 20 means for supporting the first end coils of the spring to cause the load to act on the screws at right angles to the longitudinal axes of the screws, said supporting means comprising curved clips secured to said 25 heads by said screws and having projections located adjacent the inner surfaces of such end coils, and also having flanges engaging said heads to prevent displacement. 30

WILLIAM L. McGRATH.
